UNITED STATES PATENT OFFICE.

WALTER C. MINNIEAR, OF KANSAS CITY, MISSOURI.

GAS-GENERATOR.

1,146,764.

Specification of Letters Patent. Patented July 13, 1915.

Application filed December 17, 1913. Serial No. 807,262.

To all whom it may concern:

Be it known that I, WALTER C. MINNIEAR, a citizen of the United States, residing at Kansas City, in the county of Jackson and 5 State of Missouri, have invented certain new and useful Improvements in Gas-Generators, of which the following is a specification.

My invention relates to improvements in gas generators, and my principal object is to 10 provide a simple, inexpensive, apparatus of this character wherein crude oil and water may be quickly and economically generated into gas for heating, lighting and power purposes.

One important feature of the invention resides in a combined furnace and retort in 15 which the oil comes into direct contact with the fire, to the end that said oil may be instantly vaporized with a small consumption of fuel. A further advantage in bringing the oil into direct contact with the fire, resides in the fact that the nonvolatile elements are consumed, thereby adding to the fuel and at the same time eliminating 20 impurities from the gas to the end that the latter will not have to be subjected to the usual purifying process.

Another feature of the invention resides 25 in a boiler surrounding the retort, so that heat radiating from the latter generates steam in the former which is conducted to the retort and coming into direct contact with the fire is generated into a fixed water-gas which intermixes with the oil-gas.

Other features of the invention will hereinafter appear, and in order that said invention may be fully understood, reference will 30 now be made to the accompanying drawing, in which:

Figure 1 is a plan view of the apparatus. Fig. 2 is a cross section on line II—II of Fig. 3. Fig. 3 is a front elevation of the apparatus. Fig. 4 is a central vertical section on line IV—IV of Fig. 1.

1 designates the combined retort and furnace, the lower portion of which is provided 45 with a grate 2 and an ash-pit 3. Beginning at the grate 2, the combined retort and furnace is lined upward a suitable distance with fire-brick 4 to protect its outer shell from burning out. Access is had to the ash-pit 50 3 through a door 5 and access is had to the grate through a door 6.

7 designates a flue leading upward from 55 the top of the combined retort and furnace and normally closed by a damper 8, one end

of which is weighted with a ball 9, so that gas cannot escape through said flue during the gas generating process.

10 designates an inlet pipe leading into 60 the ash-pit 3, for the purpose of admitting an air-blast when coke or similar fuel is employed, or for admitting fuel gas when coke is not used for fuel purposes.

11 designates an outlet pipe leading from 65 a point just above the grate 2 for conducting the manufactured gas from the combined retort and furnace 1.

The oil to be manufactured into gas is 70 introduced into the top of the combined retort and furnace through feed-pipes 12, and discharged directly upon the fire.

13 designates the boiler which surrounds 75 the combined retort and furnace 1 and the lower portion of its flue 7. By surrounding 80 the combined retort and furnace with the boiler 13, the water in the latter is not only economically generated into steam by heat from the former, but also prevents said combined retort and furnace from burning out. Boiler 13 is provided with the customary 85 pressure-gage 14, safety-valve 15, blow-off valves 16, and water-gage 17. Steam from the boiler 13 is conducted to the combined retort and furnace 1, through pipes 18 equipped with valves 19 to control the flow 90 of steam therethrough. Water is admitted to the lower portion of the boiler through an inlet pipe 20.

The upper central portion of the boiler 95 is provided with a water chamber 21 to prevent the flue 7, passing therethrough from burning out.

The operation briefly stated is as follows: When coke or other fuel is employed for 95 heating purposes, it is thrown into the combined retort and furnace 1, to the proper depth, through the flue 7 and then ignited, the damper 8 being left open for draft purposes. The fire is then fanned to an incandescent heat by an air-blast admitted through inlet pipe 10, after which the damper 8 is closed. The oil to be vaporized is then admitted through the feed-pipes 12, directly upon the incandescent fire, and instantly converted into an oil-gas which escapes through the outlet pipe 11 into a gasometer or other receptacle, (not shown). While the oil is being generated into gas, steam is generated in the boiler 13 by heat 100 radiated from the retort 1, and on attaining a certain pressure is admitted simultane- 105 110

ously or alternately with oil to the combined retort and furnace 1, where, in its passage to the outlet pipe 11, it passes through the incandescent fire and is instantly generated into a fixed water-gas which combines with the rich oil-gas.

From the foregoing description, it is apparent that I have produced a gas generator embodying the features of advantage above 10 enumerated, and while I have shown and described the preferred form of my invention, I of course reserve the right to make such changes in the construction, combination, and arrangement of parts as properly fall within the spirit and scope of the claim.

Having thus described my invention, what I claim and desire to secure by Letters Patent is:

20 In a gas generator, a combined retort and furnace, a boiler surrounding the retort and furnace, the upper end of the retort being

spaced from the top of the boiler, a flue rising from the retort and extending through the top of the boiler, a water chamber located in the boiler and surrounding that part of the flue between the top of the retort and the top of the boiler, oil feeding pipes extending through the water chamber and discharging into the retort and furnace, steam pipes leading from the top of the boiler and extending through the water chamber for discharging steam into the retort simultaneously or alternately with the oil, and means located above the furnace grate for the escape of gas generated in the 35 retort.

In testimony whereof I affix my signature, in the presence of two witnesses.

WALTER C. MINNEAR.
